UNITED STATES PATENT OFFICE.

ELITH C. MADSEN, OF HAZLETON, PENNSYLVANIA.

ASH, CINDER, AND COAL SEPARATOR.

1,351,861.

Specification of Letters Patent. Patented Sept. 7, 1920.

Application filed August 19, 1918. Serial No. 250,532.

To all whom it may concern:

Be it known that I, ELITH C. MADSEN, a citizen of the United States, residing at Hazleton, in the county of Luzerne and State of Pennsylvania, have invented certain new and useful Improvements in Ash, Cinder, and Coal Separators; and I do declare the following to be a full, clear, and exact description of the invention, such as will enable others skilled in the art to which it appertains to make and use the same.

My invention has for its object to provide a simply constructed and inexpensive, yet a highly efficient and durable device for separating ashes, coal, cinders and clinkers, a glass chute being provided upon which the cinders and the like and the coal are dropped, the nature of the glass causing the cinders, clinkers and the like to slide from the chute, whereas the coal will rebound to a remote point.

With the foregoing in view, the invention resides in the novel construction and arrangement of parts herein fully described and claimed, reference being made to the accompanying drawings which form a part of this specification.

Figure 1 is a side elevation of the separator;

Fig. 2 is a vertical transverse section on the plane indicated by the line 2—2 of Fig. 1;

Fig. 3 is a central longitudinal section; and,

Fig. 4 is a detail transverse section on the plane of the line 4—4 of Fig. 3.

In the drawings above briefly described, the numeral 1 designates a horizontally elongated sheet metal casing formed of upper and lower sections 2 and 3 respectively, the side walls of the lower section 3 having their upper edges bent inwardly, and then downwardly and upwardly to form upwardly facing channels 4 receiving beads 5 on the lower edges of the upper section 2, the latter being by preference of the arch shape shown in Fig. 2. One end of the casing 1 by preference inclines downwardly and outwardly at 6 and from the bottom of the casing adjacent this inclined end, an open-ended branch 7 depends. The casing bottom is provided with an ash outlet sleeve 8 adapted to fit into the upper end of an ordinary ash can 9, and from said sleeve, a hopper 10 extends for guiding the ashes into the can from a revolving separator or screen

11 mounted in the casing 1 upon a shaft 12 having an operating crank 13.

An inlet chute 14 at one end of the casing and carried by the upper section 2 thereof, discharges into one end of the screen 11, said chute being preferably provided with a dust confining cover 15. From the opposite end of the screen 11, a chute 16 inclines downwardly to the branch 7, said chute discharging onto a transverse chute 17 formed of glass. The chute 17 is disposed a considerable distance below the adjacent chute 16 and the latter drops the cinders and coal onto the former. Due to the nature of the glass chute, the coal will rebound therefrom onto another chute 18 which projects through one side of the branch 7, while the cinders, clinkers and the like will slide from said glass chute into the branch and be deposited from the latter into a suitable receptacle which may be placed thereunder.

From the foregoing, taken in connection with the accompanying drawings, it will be seen that although the device is of comparatively simple and inexpensive nature, it will be highly efficient and desirable. Particular emphasis is laid upon the provision of the glass chute 17 and its relation with the other parts, since by the provision of such a chute, the coal is effectively separated from the cinders and clinkers, and it is practically impossible to obtain this result in any other way when using a dry separator. Since probably the best results are obtained from the details and arrangement shown and described, they are preferably followed, but within the scope of the invention as claimed, considerable latitude is allowed for making such changes as occasion may dictate.

I claim:

1. In a device of the class described, a casing having an inlet to receive ashes, cinders and unburned coal, said casing being provided with three outlets, means in said casing for separating the ashes from the coal and cinders and directing such ashes to one of said outlets, and means in said casing having an inlet to receive ashes, cinders and directing them to the other outlets respectively.

2. In a device of the class described, a casing having a main horizontal portion adapted to rest on an ash can, and a vertical portion depending from one end of said horizontal portion for disposition at the ex-

terior of the can, the lower end of said vertical portion being open and forming a cinder outlet, the bottom of said horizontal portion having an ash outlet, a hopper in
5 said horizontal portion discharging through said ash outlet, a screen above said hopper, an inlet at one end of said screen, a chute leading from the other end of said screen substantially half way across the vertical
10 portion of the casing, a glass chute in said vertical portion extending transversely of said first named chute and spaced below its

delivery end to receive unburned coal and cinders therefrom, the lower end of said glass chute terminating a distance from one 15 side of said vertical portion of the casing to allow the cinders to drop, and a third chute carried by said side of said vertical portion and projecting both inwardly and outwardly therefrom to receive coal rebounding 20 from said glass chute.

In testimony whereof I have hereunto set my hand.

ELITH C. MADSEN.
